UNITED STATES PATENT OFFICE.

ELMER A. SPERRY, OF CLEVELAND, OHIO, ASSIGNOR TO THE CLEVELAND MACHINE SCREW COMPANY, OF SAME PLACE.

DESIGN FOR A VEHICLE-BODY.

SPECIFICATION forming part of Design No. 31,804, dated November 7, 1899.

Application filed September 13, 1897. Serial No. 651,545. Term of patent 14 years.

To all whom it may concern:

Be it known that I, ELMER A. SPERRY, a citizen of the United States, residing at Cleveland, county of Cuyahoga, State of Ohio, have invented and produced a new and original Design for Vehicle-Bodies, of which the following is a specification, reference being had to the accompanying drawing, forming a part hereof.

The figure is a side perspective view of a vehicle-body shaped in accordance with my present design.

This invention relates to a vendible article consisting of a body for carriages, and it constitutes a design for such body shown in the accompanying drawing. For convenience of description the body will be regarded as consisting of two parts—a main or forward part and a rear part or extension E. The main or forward part may be defined as consisting of the ordinary, paneled portion, inclosing the seat S and constituting the back of such seat. In front of the panel P, constituting the side of the seat, may be located the duster D, passing downwardly, then forward, and rising up-

ward at point d to meet the dasher A. The heel-board H reaches downward to the raised floor F, extending to the dasher. The forward surface of the dasher will be seen to be curved outwardly. The height of the floor is greater than that of the duster at point d'. The seat-line S is also higher than the top of the extension E. The distance from floor to seat S is about equal to the height a b of extension E.

The characteristic feature of the design consists in the rear extension being lower than the seat and the floor being higher than the duster at point d', and the design may be further characterized by a convex dasher.

Having described the design and pointed out its novel features, what I claim is—

The design for a vehicle-body substantially as shown and described.

ELMER A. SPERRY.
